SPRAYING APPARATUS

Duane E. Atkinson, 102 Fey Drive, Burlingame, Calif.
Filed Mar. 23, 1961, Ser. No. 97,943
8 Claims. (Cl. 239—165)

This invention relates to spraying apparatus and the like and more particularly to a device adapted to be mounted at the outer end of a swinging boom and aimed from a remote control station.

The apparatus of this invention may have many uses including that of washing the insulators on which power transmission lines are suspended from utility poles or towers. Under many conditions such insulators collect dust, water vapor, and the like which, over a period of time, decreases their insulating capacity and may cause short circuiting or grounding of the power transmission line. It is therefore common practice, especially in regions where natural rainfall is infrequent, to periodically wash such insulators with a nonconducting fluid, such as relatively pure water.

Heretofore such washing has been accomplished by supporting an operator with a fire hose at the outer end of a vehicle mounted swingable and extendable boom. Such prior apparatus has been unduly cumbersome in that it has required sufficient strength in the boom to support the operator as well as his spray equipment at an elevated position above the vehicle. In addition, the use of such apparatus also requires the employment of a vehicle operator for controlling the position of the swingable boom and moving the vehicle between the utility poles along the power transmission line.

Since the insulators to be washed may be suspended at various heights above the ground and at different locations with respect to the utility poles, the range of movement of the swingable boom carrying the operator and his spraying equipment must be considerable. The problems inherent in supporting the operator and his spraying equipment for movement over such a range of elevated positions have been further complicated by the fact that the apparatus for this use must be able to withstand being transported over relatively rugged terrain.

Although the apparatus of this invention is herein specifically described for use in washing power transmission line insulators, many other uses, such as agricultural spraying, fire fighting, mounting of optical devices, fruit picking, and the like are contemplated.

It is an object of this invention to provide means for automatically maintaining a predetermined attitude of a platform carrying a device adapted to be aimed with respect thereto.

It is another object of this invention to provide apparatus in which a device supported at the outer end of a movable boom may be aimed from a remote control station with reference to a predetermined, normal attitude.

Another object of this invention is the provision of spraying apparatus in which a nozzle, supported at the outer end of a swingable boom, may be directed by an operator from a remote ground station.

It is still another object of this invention to provide, in combination with a vehicle supported swinging boom, spraying apparatus at the outer end of the boom which may be conveniently remotely controlled from the vehicle.

A further object of this invention is the provision of means for supporting a spray nozzle for remotely controlled movement in elevation and azimuth with respect to an automatically maintained reference attitude.

Other objects and advantages will become apparent from the following description taken in connection with the accompanying drawings, in which:

FIG. 1 is a perspective and partly schematic view on a

2

relatively small scale of the apparatus of this invention; FIG. 2 is an enlarged front elevational view of the spraying apparatus support structure of FIG. 1;

5 FIG. 3 is a greatly enlarged sectional view as seen generally from line 3—3 of FIG. 2;

FIG. 4 is a sectional view as seen from line 4—4 of FIG. 3;

FIG. 5 is a cross-sectional view taken along line 5—5 of FIG. 2;

10 FIG. 6 is a semischematic view of the control means for remotely aiming the spraying apparatus of FIG. 1;

FIG. 7 is a top plan view of the mounting structure for the control lever of the control means of FIG. 6; and,

15 FIG. 8 is a side elevational view of the mounting structure of FIG. 7.

In general, referring to FIG. 1, the apparatus of this invention comprises a spraying nozzle or other device 1 mounted on a platform 2 supported at the outer end of a boom 3 carried by a ground supported vehicle 4. Vehicle 20 4 may be of the conventional type, providing a driver's and operator's cab 5 and having a conventional boom supporting structure 6. Said structure 6 mounts boom 3 for rotation about a generally vertical axis and for swinging to various positions extending upwardly of the vehicle 25 about a generally horizontal axis. Boom carrying vehicles of this type are commonly used for servicing and maintaining utility power installations and the like.

To provide the boom 3 with a substantial range of movement with respect to the vehicle, said boom is preferably of the extendable type in which a plurality of elongated boom sections 7 are mounted for sliding with respect to each other toward and away from the boom supporting structure 6. Suitable cable or hydraulic operating means, such as hydraulic cylinder 8 (FIG. 1) are 30 provided for rotating, elevating, and extending boom 3 and commonly include control means (not shown) accessible to the operator for controlling these functions of the boom. In this respect, boom 3 functions to change the elevation and attitude of platform 2 throughout the 35 range of movement of the boom.

The vehicle 4 may also carry one or more tanks 9 as a source of water or other fluid to be sprayed from nozzle 1. A pump 10 serves to supply fluid under pressure 40 through a conduit 11 extending to the outer end of boom 3. When used with an extendable boom, conduit 11 is 45 preferably a flexible hose supported on conventional reel or pulley take-up means (not shown) for taking up the slack in the hose during retraction of the boom.

The platform, generally designated 2 (FIG. 2), supporting the device 1 which is adapted to be aimed or directed, comprises a pair of decks, an azimuth deck 14 and an elevation deck 15, connected for supporting nozzle 1 for rotation about a pair of mutually perpendicular axes. A yoke 16, secured to the outer end of boom 3, 50 supports platform 2 by means of a U-shaped suspension member 17 to the central portion of which azimuth deck 14 is secured.

Azimuth and elevation decks 14, 15 are substantially 55 similar in construction and each comprises a housing 20 (FIGS. 2—4), the bottom wall of which carries externally thereof a right angle pipe fitting 21 (FIGS. 2, 4), secured thereto by flange bolts 22. Internally of housing 20, the outer sleeve element 23 of a rotatable pipe connection, generally designated 24 (FIG. 4), has its flange 60 secured to the bottom wall of housing 20 so as to communicate through an opening 26 in said bottom wall with pipe fitting 21. The inner end portion of an inner sleeve element 27 of rotatable connection 24 is received 65 in outer element 23 with the outer end extending outwardly thereof into housing 20. Element 27 is provided with peripheral races carrying ball bearings 28 supporting it for rotation within outer element 23. A threaded

cap 29 closing a radial opening in outer sleeve element 23 provides access to the races for ball bearings 28.

A packing ring 30 of flexible sealing material, such as nylon or Teflon, is clamped between the flange of sleeve element 23 and the bottom wall of housing 20 with a lip portion thereof projecting radially inwardly across the inner end of inner sleeve 27. It will be noted in FIG. 4 that a portion of opening 26 is larger than the internal bore of inner sleeve 27 to accommodate a pressure ring 31 and its backing springs 32 which serve to press the lip portion of packing ring 30 against the surface of the inner end of element 27 for sealing rotatable connection 24. An O-ring dust seal 33 may also be provided adjacent the outer end of sleeve 23.

The outer end of inner sleeve element 27 is journalled in a bearing 34 carried by the top cover 35 of housing 20, and is connected to a tubular element 36, having a flange 37 at the outer end thereof, for rotation therewith. Such connection may be by means of an externally threaded hollow element 38 received within and engaged with internal threads formed in elements 27, 36.

By the structure thus far described, means is provided supporting elements 36 for rotation with respect to their associated decks 14 and 15. Element 36 of deck 14 is secured to a right angle pipe fitting 41 (FIG. 2) which communicates with and is connected to right angle fitting 21 of elevation deck 15 by a pair of pipe nipples 42, 43 and an intervening pipe elbow 44. By this means elevation deck 15 is supported in a position normal to azimuth deck 14 and for rotation about a first axis coinciding with the axis of rotatable connection 24 and the element 36 of said azimuth deck.

A right angle pipe connection 45 (similar to connection 41) is secured to the element 36 of elevation deck 15 and carries nozzle 1 projecting therefrom in a direction normal to a second axis coinciding with the axis of rotation of connection 24 and element 36 of said elevation deck. In this manner nozzle 1 is supported for swinging about said second axis which is perpendicular to the first axis of azimuth deck 14.

Platform 2, comprising azimuth deck 14 and elevation deck 15, therefore supports nozzle 1 for rotation about said first and second axes so that said nozzle may be aimed in both azimuth and elevation orientation. Driving means for so aiming nozzle 1 are provided in each of decks 14, 15 by a motor 46 (FIG. 3) which has its shaft connected to a worm 47. Said worm is meshed with a gear 48 (FIGS. 3, 4) carried by a ring 49 fixed on inner sleeve element 27, as by a set screw 50. The motor 46 carried by azimuth deck 14 thereby serves to rotate fitting 41 and elevation deck 15 carried thereby about the first or azimuth axis, and the motor of elevation deck 15 serves to rotate fitting 45 and nozzle 1 about the second or elevation axis.

In some instances it is desirable to limit the rotation of the nozzle about these axes and each deck may therefore carry limit switches 39 (FIGS. 3, 4) connected in the electrical circuit to motor 46. Ring 49 is provided with one or more notches 40 (FIG. 4) for receiving the actuating arm roller of switches 39 for opening the switches and thereby interrupting the circuit to motor 46 at the extremities of the range of rotation selected for nozzle 1 about either the azimuth or elevation axis.

Control of such rotation of nozzle 1 about these mutually perpendicular axes for directing or aiming the nozzle stream is provided by control means (schematically illustrated in FIG. 6) which may be in the form of a conventional closed loop positional servo system. Such unit includes a control or command unit 52, conveniently located at a control station in the cab 5 (FIG. 1), and having a manual control lever 53, manipulation of which causes motors 46 to drive nozzle 1 through its azimuth and elevation arcs.

Conventionally, similar closed loop control systems are provided for each of the decks so that manipulation

of a control lever in one direction controls the movement of one deck and manipulation of the lever in another direction, or of a separate lever, controls the other deck. Each system is characterized by a signaling device which, when operated by its control lever, generates a command signal fed into a comparing means 54 (FIG. 6). Comparing means 54 performs the function of comparing the command signal with a position signal fed thereto from a position sensing device 55.

- 10 As is common practice in control systems of this type, the position sensing device disclosed herein may be a potentiometer whose wiper arm or pickoff is connected by meshed gears 51, 56 (FIG. 3) to the shaft carrying worm 47. The angular position of nozzle 1 about either the 15 azimuth or elevation axes is directly related to the angular position of the corresponding worm shaft which is transmitted through gears 51, 56 to potentiometer 55 so that said potentiometer generates a follow-up or position signal indicative of said position.
- 20 From a comparison of the command signal and the position or follow-up signal, comparing means 54 generates an error signal which may be amplified by an amplifier 57 and thereafter fed into motor 46 for actuating the same. So long as there is a difference between the 25 actual position of nozzle 1 about its axes of rotation and the position directed by the command signals from controlling unit 52, motors 46 will drive said nozzle to eliminate such difference.

In a control system of this type where the movement 30 of the nozzle is proportional to the movement of the control lever 53, it is preferable to mount the control lever so that it may be manipulated forwardly and rearwardly to control, for example, elevation and from side to side to control the azimuth position of the nozzle. An 35 operator, even if previously unskilled, may most readily acquaint himself with the proper lever manipulation to yield the desired nozzle control when the control lever is mounted in this manner. Especially in the specific illustration herein described where the nozzle is supported 40 at the end of the boom generally forwardly of the vehicle (FIG. 1), it is preferable that manipulation of the control lever forwardly and rearwardly of the vehicle controls the nozzle elevation and movement of the lever from side to side controls the azimuth position of the 45 nozzle.

A mounting structure for control lever 53 that satisfies the above purposes is illustrated in FIGS. 7 and 8. Control unit 52 includes a pair of signaling devices 58, 59 which generate the command signals fed into comparing means 54. Devices 58, 59 may be potentiometers similar to position sensing devices 55, and connected in a manner such that the motor 46 on elevation deck 15 is responsive to one of said signaling devices 58 and the motor on azimuth deck 14 is responsive to the signal 55 from the other device 59.

Control lever 53 projects upwardly from the control unit 52 (FIGS. 1, 6, 8) and is secured at its lower end to a shaft 60 (FIGS. 7, 8) journalled in the side plates 61, 62 of a mounting bracket, generally designated 63. 60 Lever 53 is therefore supported for swinging in a plane generally parallel to side plates 61, 62 of bracket 63 which also carries potentiometer 58 with its operating shaft 64 journalled in said plates. A gear segment 65 secured on shaft 60 is in mesh with a gear 66 secured 65 on shaft 64 thereby connecting potentiometer 58 for operating by swinging lever 53 in the plane of bracket 63.

Mounting bracket 63, including lever 53 and operatively connected potentiometer 58, is supported by a pair of stub shafts 67 projecting outwardly from opposed end plates 68 and journalled in bearings 69 for swinging in a second plane perpendicular to the first plane in which lever 53 swings. The base 70 on which bearings 69 are supported also carries a support 71 (FIG. 8) mounting potentiometer 59 with its wiper arm operating shaft

72 journaled for rotation about an axis at right angles to the axis of shaft 64 of potentiometer 58. A gear 73 on shaft 72 meshed with a gear segment 74 secured to shaft 67 serves to operatively connect mounting bracket 63 and therefore lever 53 with potentiometer 59.

In this manner, swinging lever 53 in the first plane of mounting bracket 63, denoted by dot-dash line 75 in FIG. 7, operates signaling device 58, and swinging said lever and mounting bracket 63 in the second, normal plane, denoted by dot-dash line 76, operates signaling device 59. Each of said signaling devices as previously described, is connected to one of the comparing means—amplifier units 54-57 of FIG. 6 so as to direct the change of position of nozzle 1 in azimuth through deck 14 and elevation through deck 15.

Assuming signaling device 58 is connected to control elevation deck 15 and signaling device 59 to azimuth deck 14, control unit 52 is preferably oriented with plane 75 extending longitudinally of vehicle 4 (FIG. 1) and plane 76 extending transversely thereof. With this relationship established it is an easy matter for a relatively unskilled operator to position the nozzle as desired by natural manipulation of control lever 53, so long as the azimuth axis is maintained generally vertical or the elevation axis maintained generally horizontal. In essence, a predetermined attitude of platform 2 must be maintained with respect to the operator's normal reference of horizontal and vertical during swinging of the boom 3 through various vertical angles which would otherwise change such attitudes.

In the specific apparatus herein described such reference is maintained by supporting platform 2 upon swingable suspension member 17 (FIG. 2). Member 17 may be a generally U-shaped tubular member having platform 2 secured to its central portion 79 and with the outer ends of its upwardly extending legs 80, 81 rotatably connected to the outer ends of yoke 16. One of said legs 80 may be so connected by a conventional self-aligning bearing 82 whereas the other of said legs 81 is so connected by a rotatable connector 83 which includes a brake means, to be described.

Suspension member 17 and platform 2, including nozzle 1, are supported with the center of gravity thereof below the aligned, generally horizontal axes of bearing 82 and connector 83. By such mounting no matter what the vertical angle of boom 3 and yoke 16, platform 14 and the elevation axis about which nozzle 1 rotates will be maintained generally horizontal by gravity in the manner of a pendulum. Such pendulum action of platform 2 about the horizontal axis of bearing 82 and connector 83 will automatically maintain the platform attitude related to the normal reference of the operator.

Connector 83 (FIG. 5) is generally similar to connector 24 in that it includes an inner sleeve member 84 the inner end of which is journaled for rotation in a cylindrical outer sleeve or housing 85 having a peripheral flange 86. Ball bearings 87 may be provided in grooved races in members 84 and 85 for free rotation thereof. A clamp 88 (FIGS. 2, 5) serves to secure sleeve 84 to the outer end of the arm of yoke 16 opposite bearing 82 with the axis of rotation of members 84, 85 aligned with the axis of said bearing. A pipe elbow 89 threadedly received in the outer end of sleeve 84 connects said sleeve with conduit 11 for passage of the fluid to said sleeve from pump 16 (FIG. 1).

A right angle pipe connection 90, having a flange 91 bolted to the flange 86 of housing 85, is connected to the upper end of leg 8 (FIG. 2) thereby supporting suspension member 17 for swinging with housing 85 about the axis of fixed sleeve 84.

In the specific apparatus herein described, the portion of suspension member 17 between connector 83 and right angle fitting 21 (FIG. 2) may form a conduit for conducting liquid to nozzle 1. Fluid under pressure from tanks 9 and pump 16 is conducted through hose

11, rotatable connector 83, suspension member 17, fitting 21, and thence through connectors 24 (FIG. 4) of platforms 14, 15 (FIG. 2), and pipe fitting 45 to nozzle 1. A conventional valve 92 (FIG. 1) is preferably provided in conduit 11 for controlling the flow of fluid from tanks 9 to nozzle 1.

Such valve may be of the solenoid actuated type and is preferably opened and closed by a control button 93 (FIGS. 6, 8) provided on the control knob 94 of lever 53. The control cable 95 (FIG. 1) which includes the wires serving to connect the signaling devices of control unit 52 to the appropriate comparing and amplifying means 54, 57 (FIG. 6) may also serve to connect control button 93 to the solenoid actuator for valve 92, as by a branch cable 96 (FIG. 1).

The issuance of fluid under pressure from nozzle 1 creates a substantial reaction force tending to swing platform 2 about its suspension axis of bearing 82 and connector 83 (FIG. 2). In order to prevent such swinging and to maintain platform 2 stable in its predetermined attitude during the spraying of fluid by nozzle 1, pressure responsive braking means is incorporated in connector 83 (FIG. 5). At its inner flanged end, adjacent housing 85, pipe connection 90 is provided with an enlarged recess 96 of larger diameter than the inside of sleeve 84. A ring seal 97 of tough, flexible packing material such as nylon or Teflon, secured between flanges 86 and 81 has an inwardly projecting lip portion 98 extending into recess 96 and across the inner end surface of sleeve 84. Said lip portion is held against the inner end of sleeve 84 by a backing ring 99 and a plurality of coil springs 100, abutting the bottom of recess 96, with sufficient pressure to render the joint fluid tight but permit a free rotation of connection 90 and housing 85 with respect to sleeve 84.

When valve 92 (FIG. 1) is shut off and no substantial fluid pressure exists in the conduit means from tank 9 to supply nozzle 1, including the passage through rotatable connector 83, suspension member 17 carrying platform 2 is free to swing and to be maintained by gravity at its normal attitude with reference to the horizontal. Under such conditions, of course, there is no jet reaction from nozzle 1. After the nozzle has been aimed at the target to be sprayed (such as the insulator in FIG. 1) as hereinbefore described, and valve 92 opened by depressing button 93 (FIG. 8), fluid under pressure will be transmitted to said nozzle through the fluid passages described. Such pressure in the fluid passage through sleeve 84 and pipe connection 90 effects a braking action on rotatable connector 83 preventing relative rotation between housing 85 and sleeve 84 (FIG. 5).

The fluid pressure in recess 96 forces backing ring 99 and lip portion 98 of seal 97 into tight frictional engagement with the inner end of sleeve 84 thereby preventing movement between said inner sleeve and said seal which is secured to housing 85. It will be noted that the braking force thereby applied to prevent rotation of connector 83 and swinging of suspension member 17 by the influence of the jet reaction of nozzle 1 is proportional to the force of such jet reaction, since both forces are proportional to the fluid pressure. The greater the jet reaction, therefore, the greater the braking action of lip portion 98 of seal 97 responsive to the pressure to lock member 17 against swinging.

It will be apparent that pressure responsive diaphragms, sleeves and the like may be alternatively employed in rotatable connection 83 for the purpose of securing suspension means 17 against swinging from its proper orientation. By employing similar rotatable connectors 24 (FIG. 4) in decks 14, 15, similar pressure responsive braking means are provided for preventing movement of nozzle 1 in azimuth and elevation during spraying with said nozzle. Pressure responsive braking means, such as herein described, is preferred for use with apparatus 70 where the device being controlled and aimed is a fluid

nozzle because the braking action is effected automatically upon transmission of the fluid under pressure to the nozzle. In apparatus wherein other devices are supported and aimed as herein described, other mechanical or electrical brakes may be employed as will appear advantageous to those skilled in the art.

It will also be noted that by combining the valve control button 93 with lever 53 of control unit 52, all functions of the apparatus, including aiming the nozzle, turning the spray on and off, and actuating the braking action for platform suspension means 17, may be controlled from a single control station by one operator.

Although not a part of this invention, it will be obvious that conventional pulley takeup means may be provided in association with the extendable boom 3 (FIG. 1) for taking up the slack in the electrical cable 95 that extends along said boom as well as for hose 11. Although the invention has been described and illustrated, in detail, various modifications that would occur as obvious to one skilled in the art are intended to come within the spirit and scope of the invention as defined by the appended claims.

I claim:

1. In spraying apparatus including a spray nozzle and a swingable boom, the combination comprising: rotatable means supporting said nozzle for rotation about a pair of mutually perpendicular axes, driving means connected to said nozzle for so rotating said nozzle about said axes, manual control means remote from said nozzle and connected to said driving means for aiming said nozzle, and means supporting said rotatable means and said nozzle at the outer end of said boom and maintaining one of said axes generally horizontal during swinging of said boom.

2. In spraying apparatus including a spray nozzle and a swingable boom, the combination comprising: rotatable means supporting said nozzle for rotation about a pair of mutually perpendicular axes, driving means connected to said nozzle for so rotating said nozzle about said axes, manual control means remote from said nozzle and connected to said driving means for aiming said nozzle, and swingable suspension means supporting said rotatable means and said nozzle at the outer end of said boom for swinging about a generally horizontal axis above the center of gravity of said rotatable means and said nozzle for maintaining one of said perpendicular axes generally horizontal during swinging of said boom.

3. In spraying apparatus including a spray nozzle and a swingable boom, the combination comprising: rotatable means supporting said nozzle for rotation about a pair of mutually perpendicular axes, driving means connected to said nozzle for so rotating said nozzle about said axes, manual control means remote from said nozzle and connected to said driving means for aiming said nozzle, swingable suspension means supporting said rotatable means and said nozzle at the outer end of said boom for swinging about a generally horizontal axis above the center of gravity of said rotatable means and said nozzle for maintaining one of said perpendicular axes generally horizontal during swinging of said boom, and means for selectively securing said suspension means against said swinging.

4. In spraying apparatus including a spray nozzle and a swingable boom, the combination comprising: rotatable means supporting said nozzle for rotation about a pair of mutually perpendicular axes, driving means connected to said nozzle for so rotating said nozzle about said axes, manual control means remote from said nozzle and connected to said driving means for aiming said nozzle, and swingable suspension means supporting said rotatable means and said nozzle at the outer end of said boom for swinging about a generally horizontal axis above the center of gravity of said rotatable means and said nozzle for maintaining one of said perpendicular axes generally horizontal during swinging of said boom, said suspension

means including a passage for transmission of fluid under pressure to said nozzle and means responsive to fluid pressure in said passage for securing said suspension means against swinging thereof.

5. In spraying apparatus including a vehicle supported, swingable and extendable boom and a spray nozzle, the combination comprising: a platform including an azimuth deck and an elevation deck respectively supporting said nozzle for rotation with respect to said platform about a first axis and a second axis normal thereto, driving means carried by said decks for so rotating said nozzle, suspension means supporting said platform at the outer end of said boom, a rotatable connector connecting said suspension means to said boom for swinging about a generally horizontal axis parallel to said second axis and with the center of gravity of said platform below said horizontal axis, and control means remote from said platform, said driving means being responsive to said control means for aiming said nozzle.

6. In spraying apparatus including a vehicle supported, swingable and extendable boom and a spray nozzle, the combination comprising: a platform including an azimuth deck and an elevation deck respectively supporting said nozzle for rotation with respect to said platform about a first axis and a second axis normal thereto, driving means carried by said decks for so rotating said nozzle, suspension means supporting said platform at the outer end of said boom, a rotatable connector connecting said suspension means to said boom for swinging about a generally horizontal axis parallel to said second axis and with the center of gravity of said platform below said horizontal axis, and control means remote from said platform, said driving means being responsive to said control means for aiming said nozzle, said connector including a passage communicating with said nozzle for conducting fluid under pressure thereto and brake means operable by fluid pressure in said passage to resist rotation of said connector.

7. In spraying apparatus including a vehicle supported, swingable and extendable boom and a spray nozzle, the combination comprising: a platform including an azimuth deck and an elevation deck respectively supporting said nozzle for rotation with respect to said platform about a first axis and a second axis normal thereto, driving means carried by said decks for so rotating said nozzle, suspension means supporting said platform at the outer end of said boom, a rotatable connector connecting said suspension means to said boom for swinging about a generally horizontal axis parallel to said second axis and with the center of gravity of said platform below said horizontal axis, control means remote from said platform, said driving means being responsive to said control means for aiming said nozzle, said connector including a passage communicating with said nozzle for conducting fluid under pressure thereto and brake means operable by fluid pressure in said passage to resist rotation of said connector, a source of fluid under pressure, conduit means connecting said passage with said source, a valve in said conduit, and said control means including a valve operator.

8. In spraying apparatus including a vehicle supported, swingable and extendable boom and a spray nozzle, the combination comprising: a platform including an azimuth deck and an elevation deck respectively supporting said nozzle for rotation with respect to said platform about a first axis and a second axis normal thereto, driving means carried by said decks for so rotating said nozzle, suspension means supporting said platform at the outer end of said boom, a rotatable connector connecting said suspension means to said boom for swinging about a generally horizontal axis parallel to said second axis and with the center of gravity of said platform below said horizontal axis, control means remote from said platform, said driving means being responsive to said control means for aiming said nozzle, said control means including a pair of signaling devices, the driving means of each of

said decks being respectively responsive to one of said signaling devices, a control lever mounting means carrying said lever and one of said signaling devices operatively connected to said lever and supporting said lever for swinging in a first plane for operating said one signaling device, and means operatively connecting said lever to the other of said signaling devices and supporting said mounting means for swinging in a second plane normal to said first plane for operating said other signaling device.
